UNITED STATES PATENT OFFICE.

BERNARD U. POTTER, OF HOLYOKE, MASSACHUSETTS.

INDICATING AND REGISTERING DEVICE.

No. 861,895.

Specification of Letters Patent.

Patented July 30, 1907.

Application filed October 8, 1906. Serial No. 338,023.

To all whom it may concern:

Be it known that I, BERNARD U. POTTER, a citizen of the United States of America, and a resident of Holyoke, in the county of Hampden and State of Massachusetts, have invented certain new and useful Improvements in Indicating and Registering Devices, of which the following is a full, clear, and exact description.

This invention relates to an indicating or registering device for showing the extents of movements of a reciprocating part in foot lengths or other units of measurement; and the device in which this invention resides has been primarily designed to show the aggregate linear extent of a succession of strokes of a piston 15 or pistons of a steam pump.

As well known, the pistons of steam pumps in usual action have strokes of slightly varied lengths, and the quantity of water delivered through the pump at each operation varies according to the lengths of the piston 20 strokes.

By being able to determine the aggregate of the lengths of all of the strokes of a piston in a pump, or of the two pistons, in a double acting pump,—fitted in a pump cylinder or cylinders of given size,—it is only 25 a matter of arithmetical computation to ascertain the cubic contents of the liquid pumped during the time in which such strokes are made.

The invention consists in the combination with a shaft and a drum loosely rotatable thereon, having a 30 tape or like flexible connection in winding engagement therearound, adapted to be connected with a piston rod or other movable part, and serving, by the movement of such rod in one direction, to impart a rotational movement in one direction to the drum, of a 35 clutch operable between the drum and shaft to engage the shaft on the rotary motion of the drum in one direction and to release such engagement on the reversed rotary movement of the drum, means for imparting a reversed rotary motion to the drum after each tape- 40 imparted motion hereof, and a shaft-rotation-meter connected with and operated by the said shaft.

The invention furthermore consists in an extension or addition of means in the device above characterized for enlarging the scope of its availability; and also 45 consists in various combinations and arrangements of parts as hereinafter described and set forth in the claims.

In the accompanying drawings, an example of a construction of the stroke measuring device produced 50 in accordance with the present invention is illustrated.

Figure 1 is a central sectional view taken through the device on the axis of the shaft thereof. Fig. 2 is a face view, with parts in section, of one of the duplicated clutch devices comprised in the device. Fig. 3 55 is a sectional elevation transversely of the axis of the device, and as indicated by section line 3—3, Fig. 1.

Fig. 4 is an elevation of the end of the device at which the meter, or shaft-rotation-indicator and register is provided; and Fig. 5 is a side elevation of a steam pump showing the position of the piston stroke 60 indicating device or register operably combined therewith.

Referring to Fig. 5 in which the steam pump shown is double-acting,—having one piston rod A working between opposite cylinders B B,—C represents the indicating device mounted on a stand above one of the cylinders and near the end thereof; and a represents a thin flexible steel tape having a winding engagement about one of the drums comprised in the new device and having a connection with a lug b carried by the stem d 70 which is affixed to, and moves horizontally backward and forward in unison with, and in the same extents as, the piston rod A.

Now it is to be understood that the present new device is to have the shaft thereof fully or partially rotated in one direction corresponding to the extent of movement to the rightward of the piston rod A, said shaft in the new device being again fully or partially rotated in the same direction on the reverse stroke of the piston rod; and these rotations of the above mentioned shaft are indicated by and accumulatively registered in the meter D with which the shaft is operatively engaged or connected.

Having briefly indicated the mode of application of the device in relation to the pump, as well as the object thereof, the construction of this piston-stroke-indicating device will be now particularly described.

Referring to Sheet 1 of the drawings, E represents a frame or support preferably made in the form of a cylindrical casing, constructed with feet b' b', and having 90 centrally and horizontally extended therethrough and journaled for rotation therein a shaft F. Mounted on this shaft, loosely, are two drums G and H having on the adjacent sides thereof oppositely facing bevel gear wheels J and K between and in mesh with which is a 95 bevel gear wheel, or pinion, L rotatable about the fixed axis constituted by the headed stud f which is supported in the screw plug e which in substance forms the portion of the casing E. This arrangement of gearing is such that when the rotary motion is imparted to the drum G 100 in one direction, the drum H will be oppositely rotated, and vice versa. The loosely mounted drums G and H have affixed on the sides therewith loosely and concentrically of the shaft, clutch members or cases M constructed with annular portions or rims g.

N, N² represent clutch elements affixed on the shaft, having their locations within the rims of said clutch cases and formed with ratchet like edge portions h and with shoulders i.

Each of the shouldered portions i is made with a 110 countersunk socket j within which plays the stem m having outside of said shoulder a curved shoe n; and a

spring in said socket reacts outwardly against said shoe, as indicated at σ in Fig. 2.

Pawl η shown in the present instance as in the form of rollers, are provided in the convergent spaces between the ratchet-like edges h of the shaft-carried clutch element and the internal surface of the flange g of the drum-carried clutch-case or element M .

As manifest, when a given drum is turned so that the clutch-case shown in Fig. 2 is moved in a proper direction, the roller pawls forced by the spring-pressed shoe, or held to action, between the flanges g and the ratchet edges of the shaft carried element M , cause a locking of the drum to the shaft instantly the drum commences to rotate, and a corresponding positive rotational movement of the shaft.

The drum G is made with a spiral peripheral groove r in which the steel tape a winds and unwinds, one end of this tape being screwed or otherwise secured to the drum.

20 The drum H is made with a sidewise opening chamber s within which is located a coiled spring Q , one end of which is connected to the case, as indicated at t , while the other end, as indicated at t^2 , is connected to the hub of the drum H .

25 The two sets of clutches are so applied that when the drum G is rotated by the unwinding tape properly drawn by the piston moving, for instance, to the rightward, the clutch appurtenant to the tape-engaged drum G becomes locked to the shaft F ;—the clutch appurtenant to the other drum H , rotated in the reverse direction, moving free of the shaft; and the spring is so connected between the drum H and the casing as to be wound up at this time.

Now assuming the pump piston rod A has moved 35 as far to the rightward as it may be impelled, the unwinding of the tape and rotation of drum G and shaft F becomes thereby terminated; and on the reversed stroke of the piston rod the reacting coil spring rotates the other drum H , as fast as the winding of tape will 40 permit such motion, and the clutch appurtenant to the drum H now becoming automatically locked to the shaft causes a continuation of the rotation of the shaft in the same direction as previously imparted thereto, and in an extent the same or more or less than before, 45 accordingly as to whether the leftward strokes of the piston rod is exactly the same or slightly more or less than was the previous, rightward, stroke thereof.

The meter D shown as located at one end of the casing E is of no uncommon or novel construction; for 50 any of the known and procurable kinds of registering counters may be utilized in the situation shown. This meter comprises an initial or primary shaft u , the squared extremity of which engages into a correspondingly shaped socket in the aforementioned shaft F ; 55 and such initial shaft u has a pointer u^2 revolvably moving over the face of the small dial u^3 , the circuit of which by the pointer is understood to correspond to one foot of each stroke or movement of the pump piston rod A in cases where,—as I have designed the apparatus,—the circumferance of the drum G is just one foot. If a piston stroke is nine inches in one direction the pointer u^2 will be moved three quarters way around; and if the reversed motion of the piston rod is nine 60 inches, the pointer will be moved three quarters further around in the same direction, and successive com-

plete rotations of the pointer in consequence of foot strokes of the piston rod will advance the number wheels in the register u^4 so that at any time a reading may readily be taken of the work, in foot strokes performed by the pump and the quantity of water delivered through the pump may be easily and accurately computed.

The shaft F of the new device is shown as having an axial passage v therethrough with radial ducts w at different portions along its length where lubrication is required or desirable.

The passage v opens to one end of the shaft which is externally screw threaded and at which is screw engaged a disk x having a screw threaded hole centrally thereof and part way therethrough. This disk has a radial passage y leading to an opening in the end portion of the shaft for the introduction of a quantity of lubricant, and a screw plug z closes the outer end of the radial passage y .

The part x is preferably made in the form of a disk as 85 thereby the shaft is not unbalanced.

A considerable latitude of change from the precise forms or constructions of the parts, as shown, may be made without departing from the present invention or sacrificing any of the advantages thereof; the device 90 may be utilized, while comprising means comprehended hereby, for determining the individual and aggregated lengths of piston strokes in one direction only; and the device is susceptible of uses in manner analogous to that here particularly described in situations other than relatively to the piston rods of pumps. 95

While herein the term "tape" has been uniformly employed in reference to the flexible means of winding connection with the drum G , it is almost needless to state that this term is interchangeably employed with 100 cord, cable, chain or wire.

I claim:

1. In combination, a shaft, a drum loosely rotatable thereon, a tape in winding engagement around said drum, adapted to be connected with a piston rod, and serving by 105 the movement of such rod in one direction to impart a rotational movement in one direction to the drum, a clutch operable between the drum and shaft to engage the shaft on the rotary motion of the drum in one direction, and releasing such engagement on the reversed rotary movement of the drum, a second drum also loose on the shaft having a bevel gear wheel thereon, a bevel gear wheel fixed on the first named drum, a bevel gear wheel between and in mesh with the gears on both drums, a spring for rotationally moving the second drum, and a shaft-rotation-indicator connected with and operated by the shaft. 110

2. In combination, a shaft, a drum loosely rotatable thereon, a tape in winding engagement around said drum, adapted to be connected with a piston rod, and serving by 115 the movement of such rod in one direction to impart a rotational movement in one direction to the drum, a clutch comprising an annular flanged case fixed on the drum, an element, fixed on the shaft, located within said flanged case, having a ratchet-like edge portion, and having a shoulder at one end of such portion constructed with a 120 socket, a stem playing in said socket, having outside of said shoulder a curved shoe, and a spring in said socket outwardly reacting against said shoe, a pawl consisting of a roller in the convergent space between the said ratchet-like edge portion and the internal flange wall, engaged by said shoe, means for imparting reversed rotary motion to the drum after each stroke in one direction of the piston, and a shaft rotation-indicator engaged and operated by the shaft. 125

3. In combination, a shaft having a pair of drums 130 loosely rotatable thereon, one of said drums having a tape

- in winding engagement therewith and adapted for connection with a movable part, the movement of which is to be measured, a spring for imparting a rotational movement to the other drum in the reversed direction from that imparted by the unwinding tape to the first drum, connections between the first and second drum for imparting from the rotary movement of the one drum a reversed rotary movement to the other, clutches operable between the individual drums of said shaft, each operable to cause the rotatory movement of the shaft in unison with the rotary movement positively imparted to the respective drums, leaving one drum free of its shaft while the other is clutch engaging the shaft and vice versa, and a shaft rotation indicating and registering device engaged and operated by said shaft.
4. The combination with a frame or support and a shaft rotatable therein, of a pair of drums loosely mounted on said shaft having on adjacent sides thereof bevel gear wheels and having clutch cases constructed with annular portions, a bevel gear wheel rotatably supported by the frame and mesh with both of the drum bevel gear wheels, clutch elements affixed on the shaft, having their locations within said clutch cases, and formed with ratchet like edge portions, roller pawls in the convergent spaces between such edge portions and annular portions, a tape secured to and having winding connection with the spirally grooved drum, and adapted, by the unwinding thereof, to impart rotatory movement to such drum and to the then clutch engaged shaft thereby, a coiled spring in the chambered side of the other drum having one end connected to the latter and its other secured to the frame and operable in its reaction to rotate its drum reversely from the direction of drum rotation imparted by the unwinding tape and a shaft-rotation-meter engaged and operated by said shaft.
5. The combination with a frame or support and a shaft rotatable therein, of a pair of drums loosely mounted on said shaft having on adjacent sides thereof bevel gear wheels, clutch elements affixed on the shaft, having their locations within said clutch cases, and formed with ratchet like edge portions, roller pawls in the convergent spaces between such edge portions and said annular clutch case portions, a tape having winding connection with one of the drums and adapted for connection with, and to be unwound by a movable part, the extent of motion of which is to be measured, a spring having a reversely rotating reaction on the other drum, and a shaft register connected with and operated by said shaft.
6. The combination with a frame or support and a shaft rotatable therein, of a pair of drums loosely mounted on said shaft having on adjacent sides thereof bevel gear wheels, and having affixed thereto clutch cases constructed

with annular portions, one of said drums having a spiral peripheral groove, and the other a sidewise opening chamber, a bevel gear wheel supported, for rotation, by the frame, and in mesh with both of the drum bevel gear wheels, clutch elements affixed on the shaft having their 40 locations within said clutch cases, and formed with ratchet like edge portions, roller pawls in the convergent spaces between such edge portions and annular portions, a tape secured to and having winding connection with the spirally grooved drum, and adapted, by the unwinding thereof, 45 to impart rotatory movement to such drum and to the then clutch engaged shaft thereby, a coiled spring in the chambered side of the other drum having one end connected to the latter and its other secured to the frame and operable in its reaction to rotate its drum reversely from the direction of drum rotation imparted by the unwinding tape and a shaft-rotation-meter engaged and operated by said shaft.

6. In a device of the character described, the combination with a shaft-rotation-indicator, and a shaft connected 55 with, and, by its rotation, actuating the indicator, two drums loosely rotatable relatively to said shaft, means reversely operable on said drums for imparting positive rotative movements thereto in reversed directions, a clutch appurtenant to each drum and operable to lock it to the 60 shaft to turn the latter each time the drum is turned by the positive rotative movements thereof, and means interoperating between the drums whereby the positive rotative movement of one imparts a reversed rotative movement to the other, and vice versa.

Signed by me in presence of two subscribing witnesses.

BERNARD U. POTTER.
